(57) **CLAIM**

The ornamental design for a foldable bicycle, as shown and described.

DESCRIPTION

FIG. 1 is a front perspective view of a foldable bicycle showing my new design in a first configuration.

FIG. 2 is a front elevational view thereof.

FIG. 3 is a rear elevational view thereof.

FIG. 4 is a further front perspective view thereof.

FIG. 5 is a top plan view thereof.

FIG. 6 is a left side elevational view thereof, the other side being a mirror image thereof.

FIG. 7 is a front perspective view of the foldable bicycle showing my new design in a second configuration.

FIG. 8 is a rear elevational view thereof.

FIG. 9 is a top plan view thereof; and,

FIG. 10 is a right side elevational view thereof, the other side being a mirror image thereof.

The broken line showing of portions of the foldable bicycle is for environmental illustration only and forms no part of the claimed design.
